UNITED STATES PATENT OFFICE

HARRY H. EVERHARD, OF CANTON, OHIO

GUIDE FOR SLIDABLE WINDOW SCREENS

Application filed June 28, 1930. Serial No. 464,576.

The invention relates to window jambs and window screens therefor, and more particularly to guide means associated with the window jambs for maintaining a screen in more than one position.

It is customary to provide windows with fly screens in the summer time and sometimes with ventilating screens in the wintertime, and such screens in common use may be divided into two general classes or groups, as follows:

Custom built screens of rigid frame construction which are built to order to fit a particular window, and which may be full length screens covering both window sashes, or half screens covering the lower sash only; and

Stock window screens which may be laterally adjustable, so that one size of screen may fit a variety of sizes of window jambs.

The custom built screens, either half or full length, are relatively expensive due to the fact that they are built to order to fit a particular window and consequently they have not been used to any extent in the more modest homes. Moreover, when such screens are mounted in the window they are usually left undisturbed for the entire season, as it is inconvenient and troublesome to remove them. Therefore the windows covered by such screens usually go unwashed for the entire season, and the performance of such acts as watering plants in window boxes, adjusting awnings, etc., must be done from the exterior of the house, instead of being accomplished much more conveniently from the interior through the open window.

Stock screens are more often of the laterally adjustable type, for the reason that while window jambs are made in various standard sizes, it has been found in actual practice that window openings of the same standard size vary as much as three-eights of an inch, and that the horizontal and vertical jamb members are nearly always considerably out of plumb, that is, they are not at right angles to each other.

Therefore the use of a non-adjustable stock screen of rigid frame construction, supposedly adapted to fit a standard size window jamb opening, results in practically as ex-

pensive a proposition as the use of custom built screens.

A so-called hump-spring style of sliding half screen has been in common usage, and embodies U-shaped spring members at the 55 sides of the screen and frictionally engaging guides on the window jamb for the purpose of maintaining the screen in any desired position. This construction necessitates closely fitting the screen frame to the window 60 opening, and is seldom satisfactory after continued use due to the fact that the springs deteriorate in the weather and do not support the screen properly after they have worn a 65 smooth track in the guides.

The laterally adjustable stock screens are, while relatively inexpensive, unsatisfactory in many cases. Such a screen is usually inserted when the lower sash is open and positioned under the upper sash between the parting strips and the inside stop strips of the window jamb. Thus the screen must be taken out of the window jamb every time it is desired to close the window or reach out 70 of the lower sash window opening from the inside thereof.

Accordingly such screens do not possess the advantages of permitting the opening and closing of the window without removing the screen, as in the case of custom built 75 screens fitted in the window jamb on the outside of the sashes.

It has been proposed to mount such an adjustable screen in retaining guides secured to the parting strip, and while such an arrangement permits movement of the lower sash, it requires the cutting of slots in the parting strip of the upper sash to permit lowering of the upper sash. This is a relatively difficult operation since the slots must be cut the size and shape of the retaining guides and since the guides must have sufficient clearance in the slots to permit easy movement of the upper sash, and yet not 85 enough clearance to admit flies and smaller insects.

Moreover, with either type of adjustable screen above described, the screen must be removed from the window jamb or guides if 100

it is desired to wash the entire window, or if it is desired to reach out of the lower sash opening from the inside.

An object of the present invention is to provide guide means for mounting stock screens of non-adjustable or rigid frame construction in standard size windows, which will compensate for the variations in the window openings, thus permitting the manufacturer or dealer to keep a large stock of standard size screens on hand for each standard size of window jamb, thus materially reducing the cost to the consumer.

Another object is to provide guide means for mounting the screen, which guide means may be secured in any window jamb outside of the window sashes, so that each sash may be raised and lowered without disturbing the screen.

A further object is to provide guide means which may be mounted in the window jamb for slidably mounting a stock screen of rigid frame construction, whereby the screen may be raised or lowered to permit washing of the window panes, or to permit reaching out of the window opening from the inside, without removing the screen from its guides.

A still further object is to provide means for maintaining the screen in its up or open position in the guides, without depending upon springs or frictional engagement with the guides.

And finally, it is an object of the present invention to provide guide means for slideable stock screens, which means are simple and inexpensive to construct, and which combine the advantages attained by the use of custom built screens and adjustable stock screens.

These and other objects are attained by the parts, improvements, and combinations which comprise the present invention, and which are particularly and distinctly pointed out and set forth in the appended claims, forming part hereof.

The invention in general terms may be stated as including guide means secured to the window jamb outside of the sashes, slidably engaging each side of the screen frame member, and each comprising an upper and lower channel member open at abutting ends, and positioned so as to form a continuous vertical channel for the screen frame, the upper channel member increasing in width from top to bottom to form an angularly disposed channel for permitting withdrawal of the screen, and adjustable retaining means at the bottom of each upper guide channel for maintaining the screen in its raised position if desired.

A preferred embodiment of the invention is illustrated in the accompanying drawings forming part hereof, in which

Figure 1 is an elevation of the exterior of an ordinary double sash window, showing

the improved screen slidably mounted in the guides in closed position;

Fig. 2 is a sectional view as on line 2—2, Fig. 1;

Fig. 3 is an enlarged fragmentary elevation similar to Fig. 1 showing the adjustable retaining members swung to permit withdrawal of the screen;

Fig. 3a is a fragmentary elevation of the guide with the screen removed as on line 3a—3a, Fig. 3;

Fig. 4 is a fragmentary elevation similar to Fig. 1 showing the screen maintained in its raised position by the retaining members;

Fig. 5 is a sectional view as on line 5—5, Fig. 4;

Fig. 6 is a fragmentary elevation similar to Fig. 1 showing the manner of inserting or withdrawing the screen in or from its guides;

Fig. 7 is a sectional view as on line 7—7, Fig. 6;

Fig. 8 is a perspective view of the upper guide member and a portion of the lower guide member, showing the inner ends thereof in a position about to be abutted with each other.

Similar reference numerals refer to similar parts throughout the drawings.

The improved guide to which the invention pertains is adapted to be mounted in a window frame of usual construction indicated generally at 10 and having the side frame members 11, a top frame member 12 and a sill member 13. The frame members have attached thereto in the usual manner the parting strips 14, the outside guide strips 15, and the inside guide strips 16.

The improved guide members are indicated generally at 17 in Figs. 1 to 8, and preferably include upper guide channel members 18, and lower guide channel members 19. Each guide member 17 is preferably secured as by means of nails or screws to the outside guide strip 15 of each frame member 11.

The window frame 10 preferably encloses an upper sash 20 slidably mounted in the channel formed between the inside guide strip 16 and the parting strip 14, and a lower sash 21 slidably mounted in the channel formed by the outside guide strip 15 and the parting strip 14.

Each lower screen frame guide member 19 is U-shaped in cross section and of uniform width throughout its length, and has side flanges 22 and 22' and the web 23. The width of each member 19 is such that the flanges 22 and 22' will slidably engage the side frame member of the screen when the latter is inserted therein. Each web 23 has apertures 24 formed therein and is secured to one outside guide strip 15 at the side of the window frame in such a position that the plane of the outside face of each flange 22 substantially coincides with the plane of the inner

edge of each strip 15, so that the lower ends of the guide members 19 abut the sill 13, and so that their upper ends preferably terminate below the upper sash when the same is located 5 in closed position.

Each upper screen frame guide member 18 is U-shaped in cross section, having the side flanges 25 and 25' and the web 26, and tapers from a width at its upper end substantially 10 equal to that of guide member 19 to a width substantially twice as great at its lower end. Each web 26 has apertures 24 formed therein for attaching the same to an outside guide strip 15, and the guide members 18 are positioned above guide members 19 so that the outside face of each flange 25 substantially coincides with the plane of the inner edge of each strip 15.

The lower end of each upper guide member 20 18 is preferably notched as at 27 to receive the upper end of lower guide member 19, and the guide members 18 and 19 are positioned on the strips 15 as shown in Figs. 5 and 7 so that their flanges 25 and 22 respectively form 25 a continuous guide flange for the screen frame, which guide flange will just clear the sash 20 when the latter is moved up or down. Each upper guide member 18 is preferably of such length as to terminate below the top 30 of the window frame when positioned so that its lower end abuts the upper end of guide member 19.

An L shaped screen retaining member 28 is pivotally mounted as at 29 upon the lower portion of each side flange 25' of each guide member 18. Each side flange 25' is bevelled as at 30 to permit the member 28 to be swung downwardly, and the depending web portion 31 formed by the notch 27 acts as a stop to 40 limit its downward movement, as best shown in Fig. 3. When the member 28 is in its down or screen retaining position, (Figs. 2 and 5) the lower end thereof is below the upper end of the outer flange 22' of the lower guide 45 member 19.

The screen indicated generally at 32 is preferably of the non-adjustable rigid frame construction disclosed in my prior Patent No. 1,708,363, dated April 9, 1929, for window 50 screens, but other types of stock screens might be used without departing from the scope of the present invention.

The screen 32 may be manufactured in such sizes for standard size window jambs as will 55 give a substantial clearance between the screen frame side members and the outside guide strips 15 of the window frame, so that when the screen is inserted in the screen guides 60 17, the variations and irregularities in the window jambs will be compensated for, and the clearance between the screen frame and the web members of the screen guides will be covered by the side flanges of the guides.

65 Thus the manufacturer or dealer is enabled

to keep a large stock of screens for each standard size of window jamb, and he may conveniently stock large quantities in the off season, which will materially reduce the cost to the consumer, as compared with the method of making screens to fit each particular window. 70

In Figs. 1 and 2 the screen 32 is shown slidably mounted in the guides 17, and in its lowered or closed position with its top frame member closely adjacent the lower meeting rail 33 of the upper sash, so as to substantially prevent insects from entering into the house between the screen and the meeting rail. The retaining members 28 are shown 80 in their screen retaining positions.

The screen 32 may be easily raised at any time, its side frame members slidably engaging at their upper portions the flanges 25 of the upper screen guide members 18 and their lower portions slidably engaging the side flanges 22 and 22' of the lower screen guide members 19. When the screen 32 has been raised sufficiently to clear the upper end of the screen guide 19, the lower end of the screen may be pushed outwardly due to the increased width of the lower end of the guide 18. When released in this position the screen may be retained by the members 28, in the position shown in Figs. 4 and 5, to permit a person on the inside to reach out through the window opening for the purpose of watering plants, adjusting awnings, and the like. 90 When the screen is thus retained in raised position by the members 28, the upper ends of the flanges 22' act as lateral stops to hold the lower portion of the screen away from the inner flange 25 of the upper guide member 18. 95

If it is desired to remove the screen from the window, for washing the window panes, the same may be accomplished by raising the screen 32 to clear the lower guide member 19, and rotating the stops 28 to the position shown in Figs. 3, 6, 7 and 8, when by pushing outwardly on the lower end of the screen the same may be withdrawn angularly past the top of the guide 19 in the manner shown in Figs. 6 and 7. 105

In the same manner the screen may be inserted in the guides. 110

Since the frame guide members 17 are mounted upon the outside window guides 15, both sashes may be raised and lowered at will without disturbing the screen so that the present improvement possesses the advantages of custom built screens. 120

It will be seen that the present arrangement attains all the advantages of custom built and of adjustable screens, and the screen guide members may be simply and economically manufactured. 125

It is understood that various modifications in the construction and arrangement of the present invention may be made without de- 130

parting from the scope of the invention as defined in the appended claims.

I claim:

- 5 1. For use with a window having upper and lower sashes and a window screen for the lower sash, a guide member for the screen adapted to extend substantially throughout the height of both sashes including upper and lower channel portions, an inside flange for the upper and lower channel portions, an outside flange for the lower channel portion located in parallel relation to the inside flange, an outside flange for the upper channel portion angularly disposed to the inside flange 10 having its lower end laterally offset from the inside flange a greater distance than the upper end of the outside flange of the lower channel portion to form an opening between said outside flanges for entering a screen into 15 the guide member, and retaining means movably mounted on the guide member for closing the opening.
- 20 2. For use with a window having upper and lower sashes and a window screen for the lower sash, a guide member for the screen adapted to extend substantially throughout the height of both sashes including upper and lower channel portions, an inside flange for the upper and lower channel portions, an outside flange for the lower channel portion located in parallel relation to the inside flange, an outside flange for the upper channel portion laterally offset from the inside flange having its lower end extending to a 25 point adjacent the upper end of the outside flange of the lower channel portion and laterally offset from the inside flange a greater distance than the upper end of the outside flange of the lower channel portion to form an opening between the outside flanges for entering a screen into the guide member, and retaining means pivotally mounted on the guide member for closing the opening.
- 30 3. For use with a window having upper and lower sashes and a window screen for the lower sash, a guide member for the screen adapted to extend substantially throughout the height of both sashes including upper and lower channel portions, an inside flange for the upper and lower channel portions, an outside flange for the lower channel portion located in parallel relation to the inside flange, an outside flange for the upper channel portion laterally offset from the inside flange 35 having its lower end laterally offset from the inside flange a greater distance than the upper end of the outside flange of the lower channel portion to form an opening between the outside flanges for entering a screen into the guide member, retaining means pivotally mounted on the guide member for closing the opening.
- 40 4. For use with a window having upper and lower sashes and a window screen for the lower sash, a guide member for the screen adapted to extend substantially throughout the height of both sashes including upper and lower channel portions, an inside flange for the upper and lower channel portions, an outside flange for the lower channel portion located in parallel relation to the inside flange, an outside flange for the upper channel portion laterally offset from the inside flange 45 having its lower end laterally offset from the inside flange a greater distance than the upper end of the outside flange of the lower channel portion to form an opening between the outside flanges for entering a screen into the guide member, retaining means pivotally mounted on the guide member for closing the opening to retain the screen in raised position, and the upper end of the outside flange of the lower channel portion extending above 50 the lower end of the retaining means when in

retaining position to form a lateral stop for the screen when the screen is in raised position.

In testimony that I claim the above, I have hereunto subscribed my name.

HARRY H. EVERHARD.
